UNITED STATES PATENT OFFICE.

WILLIAM W. BIRNSTOCK AND CHARLES W. VOGEL, OF YORK, PENNSYLVANIA,
ASSIGNORS TO HENCH & DROMGOLD COMPANY, OF YORK, PENNSYLVANIA.

BOTTLE-CRATE.

1,259,348.

Specification of Letters Patent. Patented Mar. 12, 1918.

Application filed November 14, 1917. Serial No. 202,047.

To all whom it may concern:

Be it known that we, WILLIAM W. BIRNSTOCK and CHARLES W. VOGEL, citizens of the United States, residing in the city of 5 York, in the county of York and State of Pennsylvania, have invented certain new and useful Improvements in Bottle-Crates, of which the following is a specification.

Our invention relates to that class of bottle crates in which the bottom as well as the partitions into which the interior of the box is divided for receiving individual bottles are formed of wire, and it consists of certain improvements in the means for attaching the longitudinal wires to the ends of the box, and the cross wires to the sides of the box, and also in the means for uniting together, at the points where they cross each other, the longitudinal and transverse partition wires which form the grid for reception of individual bottles.

The improvements can best be explained and understood by reference to the accompanying drawings in which:

25 Fig. 1 is a perspective view of a crate embodying our improvements, one of the sides of the box being partly broken away,

Fig. 2 is a longitudinal vertical section of the same partly in elevation on line 2—2

30 Fig. 3,

Fig. 3 is a transverse vertical section partly in elevation on line 3—3 Fig. 2,

Fig. 4 is a horizontal section partly in elevation on line 4—4 Fig. 3,

35 Fig. 5 is a detached view of one of the hook and staple fastenings for securing the longitudinal wires to the ends of the crate, and

Fig. 6 is a detached view of one of the 40 fastenings for securing the cross wires of the upper grid to the sides of the box.

Our crate A, has a wire bottom B, a wire upper grid C and also, as a precautionary measure to prevent the bottles from jostling or striking against one another when shaken about during transportation, a middle or intermediate grid D, between the top grid C and the bottom B.

50 The wire bottom is composed of longitudinal wires stretched taut between and secured at their ends to the end pieces of the crate A, by what may be termed hook and

staple fastenings, one of which is shown detached from the crate in Fig. 5.

There is one of these hooks *a* on each end 5 of each longitudinal wire of the bottom B as well as of both grids C and D and for each hook there is a staple like bar *b*, having ends *b'* bent as the legs of a staple and a slight inward bend *b''* in the bar *b* about 60 midway between the legs, to form a seat for the hook when it engages the bar. There is in the end piece of the crate a horizontal slot *c* which extends clear through from the inside to the outside of said end piece and 65 is of sufficient width to permit the passage of the hooked end *a* of the wire; and intersecting this slot at right angles is a vertical saw kerf or slot *d* extending from the outside part way only through said end 70 piece, the width and length of this slot or kerf being sufficient to admit the staple *b* snugly therein, and its depth being such that the staple, when introduced into and driven home in said slot, will be housed 75 therein so that neither it nor that portion of the hook which passes around it, will project beyond the outer face of the end piece of the crate. Each end piece of the crate is formed with a set of these intersecting slots 80 *c, d*, for the hooked end of each longitudinal wire it is to hold. In putting the crate together the hooked ends of the several longitudinal wires are inserted into and through their appropriate horizontal slots *c* so that 85 the hooks shall project to the outside of the end pieces of the crate far enough not to interfere with the insertion of the staples into their appropriate slots; the stapled bars *b* are then inserted in their appropriate vertical slots *d* and may be driven home therein, the legs *b'* of the bars being driven into the end pieces of the crate and holding the staple bars *b* tightly in place. Then by spreading the end pieces of the crate apart, 95 as for example by introduction of the side pieces of the crate between the rabbeted ends of said end pieces, the hooks and staple bars will be caused to approach and engage one another, each bar entering its appropriate 100 hook, which finally brings up against, and seats itself in the central inward bend *b''* of the bar. This fastening which is employed to attach the ends of the longitudinal wires

of the bottom, and of the two grids to the ends of the crate, and is more particularly adapted for that use, is simple, strong, durable and easy and convenient of application.

5 The end pieces X of the crate are each made in one piece. The side pieces of the crate are each made of two longitudinal pieces Y, fitted together so that in each side 10 piece the lower longitudinal edge of the top portion Y, meets and rests upon the upper edge of the bottom portion y.

The top wire grid is located in the plane of the joint between the two pieces y which 15 compose each side of the box. The cross or transverse grid wires, have each a hook-like formation e at each end, the legs of the hook being at some little distance apart from, but parallel with, one another. With 20 the thus-formed ends are associated individual anchoring members, one for each end of each cross wire, detachably engaging the ends of the cross wire, and adapted to enter vertical recesses or slots formed for their reception in the meeting edges of the two side 25 pieces which compose each side of the box, and to thus anchor the wires in place. The anchoring member which may be of any suitable form and construction, in the present 30 instance is represented as consisting of a disk or washer f, of any suitable shape, in this instance circular, provided with two eyes f' by which it is threaded onto the two legs of the hook, which loosely pass through 35 them, the anchoring washer f thus being held on the hook in a position at right angles thereto.

The hook is intended to lie between the meeting edges of the two parts y of the side 40 piece, and for this purpose either or both of these meeting edges may be recessed properly to receive the hook so that it shall lie flatwise in said recess. In the present instance the recess, lettered g, is formed in 45 the top edge of the lower part of the side piece, extending from the inside partway through to the outside of the box as shown and of shape and dimensions to receive and house snugly the hook laid flat-wise in it. 50 In the meeting edges of the two parts of the side piece are two matching vertical slots h, formed by a saw or other suitable means, at a point where they will meet and receive the two portions of the vertical disk f which extends above and below the hook e respectively.

There is a horizontal recess g, and a pair of vertical slots h, for each hook e and its associated washer f. And thus after the 60 hooks at the opposite ends of the cross wires of the top grid have been laid flat in their respective recesses in the top edge of the lower side piece y, with the lower half of the vertical washers in the vertical slots h

in the top edge of said lower piece, then by 65 fitting the upper side piece y down upon the lower side piece, the hooks will be covered and concealed by the meeting edges of the two side pieces y, while the vertical slots h in the lower edge of the upper one of said pieces will receive snugly the upper vertically projecting portion of their appropriate washers f, thus effectively locking the ends of the cross wires of the grid into the sides of the crate.

70 The detachable hook-connection between the ends of the cross wires and their anchoring members, permits of use of varying forms and weights of anchoring members with the same wire, as well as varying 80 gages of cross wires with the same anchoring members; and provided at all times and under all conditions an inexpensive effective and easily applied and adjusted device for the purposes indicated.

75 This style of fastening we use in practice only in connection with the top wire grid C. The middle grid D, is not subjected to such stress as the other, and requires no such style of side fastening. In this grid 90 therefore it will be sufficient to let the straight ends of the cross wires into holes properly drilled in and part way through the sides of the crate, for their reception.

85 For the purpose of tightly securing together the grid wires at the points where they cross one another, I make use of annular washers i of any suitable contour. These washers are preliminarily crimped, with two crimps extending diametrically from one 100 edge to the other of the washer and at right angles to one another, to receive the wires. They are laid between the wires which extend cross-wise of one another through their respective crimps in which they loosely lie, 105 the point of intersection of the wires being in the central opening in the annular washer, and the wire above the washer, being passed down at this point under the wire beneath, and up again to its former position on the 110 upper side of the washer; to facilitate this operation the two wires at their crossing point may have a slight bend, each bend being outwardly or in a direction away from the other, as indicated at k. The grid thus 115 loosely assembled, is placed in a die of proper conformation and is there subjected to pressure which closes the crimps in the disks or washers tightly around the wires and locks them immovably together at their 120 crossing points. Thus a perfectly solid grid is produced without any solder or other like instrumentality. The washers or disks moreover project into and cover the corners of the squares formed by the crossing wires, 125 and thus serve to close the holes or openings which after the placing of bottles in the grid would remain at those points, in this way

serving to prevent the escape through the grid of ice which might be placed thereon around the bottles.

Having described our improvements, what we claim herein as new and of our own invention and desire to secure by Letters Patent is as follows:

1. A bottle crate, having end pieces formed with individual slots extending through from the inside to the outside of the end pieces, and recesses, one for each slot, formed in the external faces of the ends, and extending at right angles to and intersecting said slots, longitudinal wires which extend between said end pieces and are provided with hook ends adapted to extend into and through the slots in the opposite ends of the crate, and staple bars adapted to fill the external recesses in the end pieces, the body of the bar extending cross-wise of the slot with which it is associated in posi-

tion to be engaged by the hook end of the wire, and the staple ends of said bar, at right angles to the body thereof, being driven tightly into the end pieces to hold 25 the staple bar in place.

2. A bottle crate having side pieces with recesses between their meeting edges and vertical slots in said meeting edges at right angles to said recesses, transverse grid wires 30 having hook formed ends seated in said recesses, and anchoring members provided with eyes through which the legs of the hooks loosely pass, the anchoring members being thus detachably held thereon in vertical position crosswise of the wires, and entering and engaging the vertical slots in the meeting edges of the side pieces. 35

In testimony whereof we affix our signatures.

WILLIAM W. BIRNSTOCK.
CHARLES W. VOGEL.
